UNITED STATES PATENT OFFICE.

WILLIAM E. SHOWALTER, OF HUNTINGBURG, INDIANA.

WHEELBARROW.

1,422,893.

Specification of Letters Patent. Patented July 18, 1922.

Application filed June 10, 1919. Serial No. 303,148.

To all whom it may concern:

Be it known that I, WILLIAM E. SHOWALTER, a citizen of the United States, residing at Huntingburg, in the county of Dubois and State of Indiana, have invented certain new and useful Improvements in a Wheelbarrow, of which the following is a specification.

This invention relates to certain new and useful improvements in wheel-barrows.

In construction work such as the building of houses or the like, a large number of wheel-barrows are usually employed for conveying the material to be used to the workers at different points. One or more runways are provided for these barrows to travel on and as a general rule consist of a number of boards laid side by side and extending transversely to the length of the runway. Due to faulty construction or to continued usage, some of these boards after a time become higher than others thus presenting a very rough or uneven surface for the barrow to travel over. From experience, I have found that it is very difficult to force the wheel of a heavily loaded barrow over these obstructions even at the expense of considerable extra effort, and the jar, incident to the contact of the wheel with these obstructions, is transmitted directly to the arms and shoulders of the operator, making the work of handling a barrow under such conditions extremely difficult and tiring.

With the foregoing in mind, I have provided the present invention, the principal object of which is to provide a novel mounting for the wheel of a barrow which will permit said wheel to yield readily upon coming in contact with an obstruction without transmitting any of the jar or strain incident to such contact to the arms and shoulders of the operator, and, in addition, will aid in forcing the wheel over such obstructions.

Another object of the invention is to so construct the wheel mounting that the same may be used in connection with any standard type of wheel barrow and may even be used in connection with other vehicles, with suitable modifications.

A further object is to provide an invention of this character which is simple and practical and offers advantages of sufficient importance to compensate for the slight advance in cost of a wheel-barrow having same applied thereto.

A still further and more specific object of

the invention is to provide a wheel-barrow having the supporting wheel thereof mounted in a sliding frame; suitable shock absorbing means being associated with said frame to permit a limited movement thereof in a rearward and vertical direction upon encountering an obstruction.

The foregoing and other objects of the invention as well as the specific construction, combination, and arrangement of the elements thereof will be more readily understood from the following description and accompanying drawings.

In the drawings:—

Figure 1 is a side elevational view of a wheel-barrow constructed in accordance with my invention;

Figure 2 is a bottom plan view partly broken away and partly in section; and

Figure 3 is a detail view of a slight modification.

In the drawings, the body of the barrow is designated at 4 and may be of any preferred construction. This body is supported upon a pair of bolsters 5 which are arranged adjacent the opposite ends thereof and in turn are supported upon the convergent handle bars 6. Bolts 7 are passed downwardly through the body 4, bolsters 5, and handle bars 6, and are provided with nuts 8 for securing these parts together. To reinforce the forward end of the body a pair of inclined braces 9 are provided, each of which has one end bolted to the body as indicated at 10 and its opposite end bolted to one of the handle bars 6 as indicated at 11.

Each of the said handle bars 6 has bolted to the inner side thereof, and at a point adjacent the rear end of the body, the upper end of a depending supporting post 12. An inclined brace 13, provided for each of these posts, has one end thereof engaged with the lower end of the post as shown and secured thereto by a bolt 14, the other end of the brace being bolted to the under side of one of the handle bars 6 by one of the bolts 7 securing the forward end of the body 4. A bar 15 connecting the posts 12 at their lower ends serves to retain these posts properly spaced apart and is secured to the posts by means of the same bolts 14 securing the lower ends of the braces 13 thereto.

Plates 16 and 17 are fastened to the upper and lower faces of each handle bar 6 at the forward end of said bar by means of bolts 11 and 18. Both of these plates project be-

yond the end of the bar and the plate 16 is bent to extend downwardly and outwardly from said end at a predetermined angle. The plate 17 is first bent upwardly as indicated at 19 to lie flat against the beveled portion 20 of the bar and is then bent at right angle to extend downwardly in spaced parallelism with the opposing portion of plate 16. Bolts 21 are passed through these two plates 10 to secure the same together and spacing sleeves 22, surrounding these bolts and confined between the plates, serve to keep the latter properly spaced apart. It should be noted here that, although the handle bars 15 6—6 are slightly convergent the projecting or inclined portions of the plates 16 and 17 of one handle bar, extend in spaced parallelism with the corresponding plate of the other handle bar. After these plates 16 and 20 17 are attached to each of the handle bars as explained, they are bent so as to extend parallel with the longitudinal center of the barrow, as indicated in Figure 2.

The supporting wheel 23 of the barrow is 25 mounted upon an axle 24, journaled in the sides of an oblong frame 25. For convenience in making this frame out of bendable metal, the same may be constructed in two pieces; one piece being bent to provide the 30 two sides and one end of the frame and the other piece providing the opposite end of the frame and having its extremities bent at right angle and bolted to the side members provided by the other piece as indicated at 35 26. Within this frame, upon one side of the wheel 23 there is provided a reinforcing and spacing brace 27 in the form of a plate extending the width of the frame and having its end bent to extend along the sides of the 40 frame; said ends being bolted to the sides as indicated at 28.

Angularly disposed slides 29 in the form of blocks are secured to the sides of the frame by means of bolts 30 and operate between the plates 16 and 17 carried by each 45 of the handle bars. Washer plates 31 positioned between these slides and the sides of the frame prevent wearing of the latter. Plates 32 fastened to the outer faces of the 50 blocks or slides 29 engage the sides of the plates 16 and 17 to retain the blocks or slides there between. Sliding movement of the slides or blocks 29 between the plates 16 and 17 is limited by the spacing bolt 22 as is obvious.

Fastened to the inner end of the frame 25 are a plurality of guide bolts 33. An end of each of these bolts is inserted through an opening provided therefor in the end of the frame and secured against movement in said opening by means of the nuts 34 threaded thereon and engaging opposite sides of the frame as shown. The opposite ends of these 60 guide rods or bolts are mounted to slide 65 through openings provided in a plate 35 dis-

posed beneath the body 1 and between the handle bars 6. A second plate 36 is mounted to slide on the rods 33 between the plate 35 and the adjacent end of the frame 25, and this second plate 36 may be adjusted longitudinally of the rods by means of the nut 37 engaging one side thereof. Encircling the rods 33 and confined between the plate 36 and 35 are the coil springs 38, the tension of which may be varied by adjusting the 75 plate 36.

The ends 39 of the plate 35 are bent at right angles as shown and bolted as indicated at 40, to the intermediate portions 41 of a pair of opposed plates 42. Each of these 80 plates 42 has the ends thereof bolted to the inner side face of one of the handle bars 6 and the intermediate portion 41 thereof bowed outwardly from said handle bar to lie flatly in engagement with the end 39 of 85 the plate 35 as shown. One end of each of these plates 42 passes between one of the posts 12 and the adjacent handle bar 6 and is held in position by means of the same bolt securing the post to the handle bar. 90

In operation, when the wheel 23 strikes an obstruction, it will be permitted to move rearwardly and upwardly carrying with it the frame 25. The slides 29 carried by the frame will move rearwardly and upwardly 95 between the plates 16 and 17 until limited by contact with the spacing bolts 22 adjacent the forward ends of the handle bars 6. This rearward movement of the frame 25 places under tension the shock absorbing 100 springs 38 and the reaction of these springs tends to force the frame forward again thus carrying the wheel over the obstruction. It will be seen therefore that the sliding frame not only acts as a shock absorber, but by 105 placing the springs 38 under tension enables these springs to exert a pushing force upon the frame sufficient to enable the same to force the wheel over the obstruction. The fact that the supporting wheel moves vertically as well as rearwardly, combined with the forward pushing power obtained by 110 placing the springs 38 under compression, enables the barrow to pass readily over the roughest sort of surface without any appreciable jarring action or strain upon the shoulders of the operator. 115

In Figure 3 I have shown the modifications which would be necessary in applying the invention to a metal wheel-barrow of the 120 type having the handle bars thereof made of tubular piping. In this form, the inner end portions of the plate 16' and 17', (conforming to the plates 16 and 17 previously described), instead of being applied to the 125 upper and lower faces of the handle bar 18' are brought together as shown and fastened to the upper face of the handle bar as indicated at 19'. This is practically the only change necessary in applying the invention 130

to a wheel-barrow of this type although it might be desirable in some instances to secure the plates 16' and 17' to the under face of the handle bar 18' instead of to the upper 5 face thereof.

Having thus fully described my invention, what I claim is:—

1. A wheel-barrow comprising a body, guides carried by said body, a sliding frame 10 supported by said guides and capable of rearward and vertical movement with respect to said body, spring means associated with said frame in such a way as to be placed under compression by the rearward and vertical movement thereof, and a supporting wheel carried by the frame and movable therewith.

2. A wheel-barrow comprising a body, downwardly inclined guides carried by said 20 body, a frame, slides carried by said frame and movable in said guides, shock absorbing springs connected with said frame, and a supporting wheel carried by the frame.

3. A wheel-barrow comprising a body, a supporting wheel, a movable frame carried 25 by said supporting wheel, guides carried by said body, slides carried by said frame, and operating in said guides, said guides being inclined to permit rearward and vertical movement of said frame and supporting 30 wheel, guide rods carried by the inner end of said frame, guide plates carried by said body and provided with openings to receive said guide rods, and springs encircling said guide rods and adapted to be placed under 35 compression by the movement of said springs, said springs serving as a shock absorber and as a means for forcing the supporting wheel over obstructions.

In testimony whereof, I have affixed my 40 signature in the presence of two witnesses.

WILLIAM E. SHOWALTER.
